UNITED STATES PATENT OFFICE

JOB HUTCHINSON, OF GREAT NECK, NEW YORK

CHANGEABLE INDICATOR

Application filed May 25, 1927. Serial No. 194,129.

This invention relates to changeable indicators and has particular reference to changeable indicators for railway stations similar to that disclosed in my Patent No. 1,345,675 issued July 6, 1920.

The primary object of the present invention is to provide an improved form of indicator which, in addition to the information displayed in the form illustrated in my aforementioned patent, shall also include means for showing the make-up of the train from the locomotive to the rear end. This information is particularly useful when a train is split up into sections as the passengers and station officials can ascertain at a glance where each particular car is located.

Another object is to provide an indicator which shall afford ready access to the display panels so that the desired information may be easily and quickly set up or removed.

A further object is to provide an indicator of the aforesaid character which shall consist of relatively few parts that are simple in construction and inexpensive to manufacture and which shall be neat and attractive in appearance.

With these and other objects in view, the invention may be stated to consist in the various novel features of construction and arrangement or combination, all of which will be fully described hereinafter and pointed out in the appended claims.

In the drawings accompanying and forming part of this application,

Figure 1 is a front elevation of an indicator constructed in accordance with my invention but showing a portion of the same removed;

Figure 1^a is a similar view showing the additional section or portion which cooperates with the structure in Figure 1 to form a complete display board;

Figure 2 is a side elevation of the apparatus;

Figure 3 is a fragmentary front elevation of the display panel;

Figure 4 is a vertical sectional view through the structure shown in Figure 1^a;

Figure 5 is a fragmentary detail elevation with parts broken away and showing the operating mechanism for the display board;

Figure 6 is a detail fragmentary front elevation of a portion of one of the chains;

Figure 7 is a side elevation of a modified form of supplemental display section;

Figure 8 is a horizontal sectional view taken on the line 8—8 of Figure 7; and

Figure 9 is a fragmentary vertical sectional view of the upper portion of the mechanism shown in Figure 7.

Referring particularly to Figures 1 and 1^a, my improved display board comprises a base 1, a main display section 2, a top 3, and a supplemental display section 4, which is interposed between the top and base and positioned adjacent the main display section 2. The main display section is designed to indicate the time of departure of the train, the name of the train, the number of the section and any other suitable information, and this section is preferably constructed in the manner described and illustrated in my aforementioned patent and hence a detailed description thereof at this time is deemed unnecessary.

The supplemental display section 4 comprises a substantially rectangular housing 6 which is bolted or otherwise secured to the main section 2, as most clearly shown in Figure 8. The housing 6 is provided on its front with an open upper portion 7 affording access to the display board and with a lower door 9 hinged at 10, which is provided with a plurality of receptacles 11 in which the letters used on the display board may be stored. A partition 12 divides the housing into upper and lower compartments and also serves to support a pair of bearing standards 13 and 14 that are arranged at right angles to each other as shown in Figure 5.

Standard 13 has journalled thereon a shaft 15 which mounts at one end a bevel gear 16, while the opposite end of said shaft is squared and terminates adjacent an aperture 17 formed in the front of the casing so that a crank may be inserted through said aperture and engage the squared end of the shaft 15 to rotate the same. Bevel gear 16 meshes with a similar gear 18 that is carried by one end of a shaft 19 which is journalled in standard 14. The opposite end of this shaft is fitted with a spur gear 20 which in turn

meshes with a similar gear 21 that is mounted on a sprocket shaft 22. Sprocket shaft 22 is journalled between the side walls of the housing 6 and carries a pair of spaced sprockets 23. Adjacent the upper end of the housing a similar shaft 24 is journalled, and this shaft is also provided with a pair of spaced sprockets 25 that are disposed in alignment with the sprockets 23 so as to receive a pair of chains 26. These chains consist of a plurality of supporting blocks 27 which are interconnected by a plurality of chain links 28. Connected to the supporting blocks by screws 29 are a plurality of transversely disposed bars 30. As shown in Figures 3 and 4, certain of these bars are formed with flat surfaces while others are formed with outwardly projecting ribs 31 having enlarged heads 32. A pair of adjacent ribs thus define a holder for suitable indicating plates 33, such plates each being formed with a lateral projection 34 so that each may be positioned by first inserting the upper edge in the groove defined by a head 32, then the lower edge is engaged over an adjacent head and the bottom edge of the plate inserted in the groove defined thereby, whereupon the plate rests upon the last mentioned head with the projection 34 in engagement therewith as shown in Figure 4.

In use, the desired information is set up on the main indicator section 2, as explained in my aforementioned patent. The supplemental indicator is intended primarily to indicate the numbers and the character of the cars in each section. This display is set up by inserting a hand crank through aperture 17 to rotate the bevel gears and chain sprockets 23 in a direction to move the bars 30 downwardly to a point where the upper portion of the display board is within convenient reach, whereupon the operator mounts the desired numbers and other data as explained above. The plates 33 bearing the information to be displayed may be conveniently stored in the receptacles 11 on the rear of the door 9, such receptacles in the present instance consisting of a plurality of drawers, as clearly shown in Figure 4. When the display is completely set up it is raised to the desired elevation by the hand crank, and such crank is then removed and stored away. It is thus obvious that the complete display board will give detailed information of the train at a glance and greatly expedite travel.

In Figures 7-9 inclusive I have illustrated a modified form of supplemental display mechanism. In this form, a transverse sprocket shaft 38 is journalled between the side walls of the housing adjacent the upper end thereof and this shaft is fitted with spaced pulleys 39 over which chains 40 hang. The front ends of the chains are connected with a plurality of interconnected bars 41, each of which is formed with a forwardly

projecting rib 42 having an enlarged head 43 to define oppositely disposed horizontal grooves for the reception of the display plates in the same manner previously referred to. The bars 41 are guided by suitable channel shaped guides 44 disposed one at each side of the casing adjacent the front of the housing, as clearly shown in Figure 8. The rear ends of the chains 40 are connected with a weight 45 that is slidably mounted in vertical guides 46 disposed at the rear of the housing. This weight serves to counterbalance the weight of the bars 41 and display plates thereon so that the display may be easily moved in a vertical direction and will remain at any desired elevation. The lower portion of the housing is similar to that previously described in connection with Figure 4. In this form of my invention, the lower door is first opened to allow the bars 41 to clear the receptacles thereon when the display is lowered. The operator merely grasps the bars 41 and pulls downwardly to a convenient elevation to insert the display plates, whereupon the entire display when set up is raised to the desired elevation by pushing upwardly on the bars 41.

I claim:

1. A changeable indicator comprising a housing, a pair of shafts journalled in spaced vertical relation in said housing, each of said shafts having a pair of sprockets arranged in spaced relation thereon, chains spaced horizontally and engaged about said sprockets, said chains each having a series of blocks interconnected by links, horizontally disposed bars fastened to said blocks and interconnecting said chains, certain of said bars having forwardly projecting ribs with enlarged heads defining upper and lower grooves, the upper groove of one bar and the lower groove of another bar being adapted to receive a display plate therein, and the distance between the bottoms of said grooves being greater than the width of said display plate to permit ready insertion and removal of said display plate.

2. A changeable indicator comprising a housing, a pair of shafts journalled in spaced vertical relation in said housing, each of said shafts having a pair of sprockets arranged in spaced relation thereon, chains spaced horizontally and engaged about said sprockets, said chains each having a series of blocks interconnected by links, horizontally disposed bars fastened to said blocks and interconnecting said chains, certain of said bars having forwardly projecting ribs with enlarged heads defining upper and lower grooves, the upper groove of one bar and the lower groove of another bar being adapted to receive a display plate therein, the distance between the bottoms of said grooves being greater than the width of said display plate to permit ready insertion and removal of said display plate.

plate, said plate having a forwardly projecting portion adapted to engage the rib on said bar to support said plate in operative position.

- 5 3. A railway train indicator comprising a main and a supplemental display section, each in the form of a column, said sections being arranged side by side in close relation, said main section having means for detachably receiving a plurality of display characters adapted to indicate general information regarding a particular train, and being provided with a base projecting to one side thereof, and said supplemental section having means for detachably receiving a plurality of display characters adapted to indicate specific information regarding that particular train and being constructed to rest upon said projecting base, and a cap surrounding said combined sections and having means to indicate the track on which that particular train may be found.
